UNITED STATES PATENT OFFICE.

JOHN W. GOCHER, OF JOHNSTOWN, PENNSYLVANIA.

ROLLER-FEED TABLE.

No. 830,990.

Specification of Letters Patent.

Patented Sept. 11, 1906.

Application filed July 11, 1905. Serial No. 269,175.

To all whom it may concern:

Be it known that I, JOHN W. GOCHER, a citizen of the United States, residing in the city of Johnstown, county of Cambria, and 5 State of Pennsylvania, have invented certain new and useful Improvements in Roller-Feed Tables; and I do hereby declare the following to be a full, clear, and exact description of the invention, such as will enable others skilled 10 in the art to which it appertains to make and use the same.

My invention relates to the construction of roller-feed tables, with particular reference to those used in connection with metal-rolling 15 mills, and more especially to the construction of the aprons between the rollers, the journal-bearings for the rollers, the side guides, and the manner of mounting them upon the frame or the side girder of the table, and 20 means for securing the various portions together.

Although for the purpose of simplifying the description of my improved apparatus I have confined the illustration and specifications thereof to a roller-feed table as designed for use in connection with metal-rolling mills, I wish it understood that my invention can be used in a feed-table for carrying or transporting any kind of material for 30 which this style of apparatus is applicable.

Certain of the objects of my invention are to provide simple and efficient caps for the journal-bearings located in position by means of dowel-pins engaging with their extremities and the side frames or girders of the table and held in place by the prolongations of the aprons which extend between the peripheries of the two adjoining rollers, each of said aprons in turn being held in place by means 40 of one large through-bolt passing through each end of same and through the main frame or side girder of the table.

A further object of my invention is to provide a construction such that the upper surfaces of the side frames, including the prolongations of the aprons (but not the removable side guides) lie in substantially the same horizontal plane, thus affording a smooth 45 surface, over which wide plates or similar material can readily pass, and a convenient plane on which to mount side guides in cases where these are necessary.

My invention also includes side guides for the table, which are used when transporting 50 narrow material or edged plates, said side guides serving to maintain the alinement of

said plates as they pass to and fro on the rollers.

My improved side guides are held in position on the main frames or side girders of the 60 table by means of dowel-pins projecting from said side guides or from brackets secured thereto into corresponding holes in the side girders, so that the mere operation of lowering said side guides vertically will place them in 65 position, and by raising them in the opposite direction they are at once removed without further manipulation.

Another and particular feature of my invention consists in the lower journal-bearing 70 for the shaft of the roller, which bearing is made of cast bearing metal—such as brass, bronze, or Babbitt—set in place in a substantially semicircular recess provided therefor in the side frame and maintained in longitudinal position by means of an annular rib on 75 the lower side of said journal-bearing, which rib fits into a corresponding groove in the frame. Each journal-bearing is held in place by a cap which rests upon the upper edges of 80 same, which cap in turn is held in place by the prolongations of the adjoining aprons, which bear upon the projecting flanges of 85 said cap.

My roller-feed table with the side guides removed is adapted for use in conveying plates which are wider than the rollers of my table, while the addition of the side guides heretofore referred to adapts my roller-table for use 90 in connection with the handling of universal or edged plates.

Referring now to the accompanying sheet of drawings, which form part hereof, and in which like characters of reference designate like parts, Figure 1 is a side elevation of a part of 95 my roller-feed table sufficient to show the construction thereof. Fig. 2 is a corresponding plan view of the parts shown in Fig. 1. Fig. 3 is a transverse vertical sectional elevation taken on the planes indicated by the broken 100 line III III of Fig. 2. Fig. 4 is a partial vertical longitudinal section showing the cross-section of the central portion of an apron and a part of the adjoining feed-rollers.

In the various drawings, 1 indicates the 105 main frames or longitudinal side girders of my feed-table, which are made, as indicated, in sections of convenient length, the opposite ones being secured together transversely by means of the through-bolts 3 and spaced 110 apart at the proper distance by the separators or thimbles 2, while 4 indicates the bolts

for securing the adjoining sections of the side girders together by means of their adjoining flanges 5.

At suitable intervals dependent upon the character and length of the pieces to be carried are located the journal-bearings 6, in which are mounted the shafts of the rollers 7, on the ends of which shafts are secured the bevel-gears 8, which are driven by the bevel-gears 9, mounted on the driving-shaft 10. The journal-bearings for the roller-shafts are provided with caps 11, in which are the oil-reservoirs 12, said journal-caps being also provided with projecting curved flanges or dust-shields 13, which extend within the shell of the roller and over the joint between the roller-hub and the bearing for same, thus excluding the dust therefrom. Dowel-pins 14 are provided, as shown, to locate the journal-bearing caps in proper position on the side girders, said dowel-pins being mounted in holes provided in the projecting flanges 15 of the journal-caps 11 and extending into corresponding holes provided in the upper surface of the side girders 1. Extending between the peripheries of the rollers are the aprons 16, the upper surfaces of which are level and in a plane slightly below the upper portion of the periphery of said rollers, said aprons serving as guides and supports when necessary for the material passing to and from said rollers. The upper surface of the apron is located a slight distance below the upper portion of the periphery of the rollers, so that just enough of the surface of said roller is exposed to properly support and traverse the piece resting upon it. The aprons 16 are provided with projecting ends 24, which, as shown in the illustration, are of trapezoidal form with horizontal upper and lower surfaces and with inclined edges. Said inclined edges are arranged to bear upon corresponding inclined edges on the projecting flanges 15 of the journal-caps 11, said aprons being held in position by means of large through-bolts 17, which pass through corresponding holes in the side girders or frame 1. This arrangement of the journal-caps, aprons with extensions, and one large through-bolt at each end of each apron securing both the apron and the journal-cap to the frame, is an important and particular feature of my invention, as by means of this arrangement the usual large number of small parts is dispensed with. I prefer to make the through-bolts 17 so large that a man with a hand-wrench cannot twist them off, and as the parts are reduced to a minimum the change and repair of any portion rendered necessary by wear or breakage is facilitated.

As the operation of roller-feed tables of this character should be continuous, the simplicity of my arrangement and the ease with which repairs or changes can be effected con-
65 due largely to the value of the apparatus.

It should also be noted that the arrangement of the bolts 17 is such that they are easily accessible, thus obviating the necessity for the repairman to go under the table or between the rollers.

The aprons 16 are further provided with flanges 18, which fit in between corresponding projections on the side girders, as shown particularly in Fig. 3, thus serving to hold the various parts in proper relation to each other.

My side guides are composed of plates 19, which extend longitudinally on each side of the table, provided with brackets 21 and dowel-pins 20, which latter are mounted in corresponding holes, as shown, in the prolongation 24 of the apron and the side girders. Any side pressure brought to bear against the plates 19 of the side guides will not dislodge them from their position; but at the same time the construction is such that by lifting said side guides vertically they can be easily and quickly withdrawn when it is desired to roll or carry wide material, and they can be quickly replaced by a reversal of this procedure when narrow material is to be transported.

The lower journal-bearings 6 are each provided with an annular rib 22, which is set into a corresponding groove formed in the recess of the side girder.

In order that the lower portion of the journal-cap 15 may rest upon and hold the lower journal-bearing 6 in place, a clearance-space 23 is provided, so that the cap will rest upon the upper edges of the lower journal-bearing, and not on the side girder adjoining same. I make the lower journal-bearings of Babbitt, brass, bronze, or other suitable material previously cast in molds and by means of my construction can readily replace a worn one by a new one when necessary.

Although I have shown the projecting ends 24 of the apron 6 as inclined, I do not limit myself to this particular arrangement, but may form the joint between the prolongation 24 of the apron and the projecting flange 15 of the journal-caps by a rabbet or right angle, offset if preferred, the essential feature being that the adjoining aprons shall project over and hold the journal-cap in position.

In order that there shall be no obstruction above the surface of the aprons and their extension, I provide recessed openings for the reception of the heads of the bolts 17, and I also make the upper surface of the journal-bearing caps 15 in substantially the same plane as that of the upper surface of the apron, thereby providing a flush construction of framework and its attachments, above which the rollers slightly project at intervals. This construction makes the table particularly applicable for conveying wide plates which project over the ends of the rollers, as may be readily understood.

In the operation of my roller-feed table the plates or other material lie on the upper surfaces of the rollers 7, which are driven in either direction at will by their connection to the driving-shaft 10, which latter is provided with any suitable source of power. For handling wide plates the side guides 19 are removed, and on account of the flush construction of the upper portion of the frame-work plates or material much wider than the rollers can be handled. The apparatus can thus be comparatively small and cheap, while at the same time effective. For handling narrow material or universal plates I prefer to place the side guides 19 in position, as shown on the drawings. As regards repairs, the principal features of my construction which require attention are the lower bearing-journals 6 and possibly the rollers themselves, which are easily and quickly replaced by unscrewing the nuts of the bolts 17, lifting a pair of adjoining aprons, and removing the journal-caps, thus allowing the rollers and the journal-bearings to be lifted and replaced.

While I have thus shown and described my invention, I do not limit myself to the exact details of the construction, but may modify the same or use equivalents thereof within its scope, as pointed out in the claims.

Having thus described my invention, what I claim, and desire to secure by Letters Patent, is—

1. In a roller-feed table the combination with the side frame or girders of journal-bearing caps for the roller-bearings, aprons extending between the rollers, the ends of which aprons overlap said caps, and means for securing said aprons to the side frame or girders whereby the journal-caps are also held in position.

2. In a roller-feed table the combination with the side girders or frames of journal-bearing caps for the rollers, aprons extending between said rollers and projecting over the ends of said journal-bearing caps, a large through-bolt passing through each end of the apron aforesaid, to secure the parts mentioned to said side girders.

3. In a roller-feed table the combination with the side girders of caps for the roller journal-bearings, said caps having inclines on their ends, aprons extending between the rollers, having extensions with inclined edges projecting over corresponding inclines on the ends of the journal-bearing caps aforesaid, a bolt passing through each end of the aprons aforesaid and securing the same to the side girders.

4. In a roller-feed table the combination with the side girders of journal-bearings mounted therein, journal-bearing caps provided with flanges having inclined surfaces, aprons extending between said rollers and having extensions provided with inclined

ends bearing upon the corresponding inclines of the journal-bearing caps and means for securing said aprons to the side girders whereby the various parts mentioned are held in position.

5. In a roller-feed table, the combination with the side girders of rollers mounted therein and projecting above the same, journal-bearing caps for said rollers, aprons extending between said rollers and overlapping the ends of said journal-bearing caps, said aprons and journal-bearing caps forming a substantially plane surface slightly lower than the upper portion of the peripheries of the rollers aforesaid, and means for securing said aprons to the side girders.

6. In a roller-feed table the combination with the side girders on which are mounted journal-bearing caps and aprons forming a substantially plane surface, of side guides mounted thereon and secured in position merely by dowel-pins passing through the projecting ends of said aprons and the side girders aforesaid.

7. In a roller-feed table including side girders, journal-bearing caps mounted thereon, and aprons extending between said rollers and projecting over said journal-bearing caps, all forming a substantially plane upper surface, side guides mounted on said upper surface of said aprons and journal-bearing caps and located in position thereon by means of dowel-pins passing therethrough.

8. In a roller-feed table the combination with the side girders of journal-bearings mounted therein, caps for said journal-bearings having dowel-pins projecting therefrom into corresponding openings in the side girders, aprons extending between the rollers the ends of which project over corresponding flanges on the journal-bearing caps, and means at the ends of said aprons for securing them and hence the other parts, to the side girders.

9. In a roller-feed table having side girders provided with journal-boxes, journal-bearing caps provided with projecting flanges having inclined ends, aprons extending between the rollers and having projections with inclined portions overlapping the corresponding inclines of the journal-bearing caps, dowel-pins projecting from the journal-bearing caps and the side girders, a through-bolt at each end of each apron for securing same to said side girders whereby the various parts are held in position.

10. In a roller-feed table the combination of side girders having journal-bearing boxes formed therein, provided with an annular groove, removable journal-bearings mounted therein and provided with a corresponding annular rib, journal-bearing caps adapted to rest on the upper edges of the lower journal-bearings aforesaid, aprons extending between the rollers and having projecting ends

overlapping the journal-bearing caps aforesaid and means for securing said aprons to the side girders, whereby the various parts are held together.

- 5 11. A roller-feed table comprising side girders provided with journal-boxes having annular grooves therein, removable journal-bearings provided with corresponding annular ribs mounted in said journal-boxes, journal-bearing caps mounted on said side girders having their lower edges resting upon the upper edges of the journal-bearings aforesaid, aprons extending between the rollers and projecting over the ends of the journal-bearing caps, a bolt at each end of each of the aprons aforesaid for securing same to the side girders whereby the various portions of the construction mentioned are held and maintained in operative position.
- 10 12. A roller-feed table comprising side girders provided with journal-boxes having

annular grooves therein, removable journal-bearings provided with corresponding annular ribs mounted in said journal-boxes, journal-bearing caps mounted on said side girders 25 having their lower edges resting upon the upper edges of the journal-bearing aforesaid, said caps having inclined ends, aprons extending between the rollers and having extensions with inclined ends projecting over 30 corresponding inclined ends of the journal-bearing caps, a bolt at each end of each of the aprons aforesaid for securing same to the side girders whereby the various portions of the construction mentioned are held and maintained in operative position. 35

In testimony whereof I hereto affix my signature in the presence of two witnesses.

JOHN W. GOCHER.
